Term of patent 14 years

Int. Cl. D22—99

U.S. Cl. D22—22

FIGURE 1 is a side elevational view of a combined fishing rod holder and signalling device, showing my new design;

FIGURE 2 is a rear elevational view thereof;

FIGURE 3 is a front elevational view thereof;

FIGURE 4 is a top plan view thereof;

FIGURE 5 is a bottom enlarged plan view thereof;

FIGURE 6 is a side elevational view of the lower portion of a modification of my new design;

FIGURE 7 is a rear elevational view of the modification illustrated in FIGURE 6.

FIGURE 8 is a front elevational view of the modification illustrated in FIGURE 6.

FIGURE 9 is a side elevational view of the lower portion of a further modification of my new design;

FIGURE 10 is a rear elevational view of the modification illustrated in FIGURE 9;

FIGURE 11 is a front elevational view of the modification illustrated in FIGURE 9.

The opposite sides of the side elevation views illustrated are subsequently mirror images thereof; the upper

portions of the modifications illustrated in FIGURES 6 through 11 are substantially the same as in FIGURES 1 to 5 and are omitted for convenience of illustration.

I claim:

The ornamental design for a combined fishing rod holder and signalling device, as shown and described.
